UNITED STATES PATENT OFFICE

2,202,907

DAUBER

Mary C. Holter, Baltimore, Md.

Application July 11, 1938, Serial No. 218,551

2 Claims. (Cl. 15—210)

The object of my invention is the providing an implement for applying polish to white shoes, but which may be used on any shoes in applying daubing material thereon without daubing the soles.

I am aware that sponge rubber has been used for this purpose, and I am also aware that Pyralin or similar flexible material has been used for backs and holding means, but neither one nor both have been used in the combination and shape as hereinafter set forth.

With the foregoing and other objects in view, my invention consists of the novel construction, combination and arrangement of parts as hereinafter specifically described and illustrated in the accompanying drawing, wherein is shown the preferred embodiment of my invention, but it is understood that changes, variations and modifications may be resorted to which come within the scope of the claims hereunto appended.

In the drawing of the herein described embodiment of my invention, Figure 1 is a perspective view of my dauber; Fig. 2 is a front elevation; Fig. 3 is an end view in elevation, illustrating the dauber in operative position to a fragmentary portion of a shoe and sole structure; Fig. 4 is a rear elevation; Fig. 5 is a plan view; Fig. 6 is an inverted plan view, and Fig. 7 is a perspective view of a woman's shoe illustrating the dauber in operative position therewith.

Similar numerals refer to similar parts throughout the several views.

1 is the back or holding element, preferably made of any suitable material, such as cellulose (Cellophane), Pyralin or Celluloid, but preferably not the latter as it is inflammable. I have even found glass or metal to be good material for this purpose, especially the rustless type of metal and alloys. 2 is the handle attached to the back or holding element 1 and may be made integral therewith. 3 is the sponge rubber daubing material held by back 1, preferably by means of adhesive, such as rubber cement, shellac, or the like, or by any other well-known means.

Back 1 is peculiarly shaped, as shown in the figures, having a concave end 4, a less concave front 5, and a convex end 6, each performing its own function in use.

The sponge rubber 3 is secured in holding element 1 by any well-known means, such as rubber cement, or the like. It is preferable to have the sponge rubber raw on four sides, or particularly on three sides away from the handle 2 for absorptive and rubbing purposes. In use back 1 contacts with the sole of the shoe, the sponge rubber 3 contacting the upper, the concave end 4 operating around the heel, the convex end 6 operating in the instep and the concave front 5 operating around the sole and together with end 4 around the toe.

The shoe having been previously cleaned of mud and dirt, the back 1 protects the sole from an application of the material to be used while a complete application is performed on the upper 20 by means of the sponge rubber.

Having thus described my invention, what I claim and desire to secure by Letters Patent is:

1. In a dauber, a plate being flanged in opposite directions forming at one end a handle and 25 at the other end a guiding and supporting element for a daubing element, said guiding and supporting element having a curved portion at its peripheral edge for guiding purposes, in combination with a daubing element secured to said plate 30 and engaging the portion between said two flanges.

2. A tool for dressing the tops of shoes comprising, a plate portion flanged near an end 35 forming a handle thereby, the other end of said plate being flanged again forming a guard and supporting element, said latter element being curved at one of its peripheral edges for guiding purposes in combination with a daubing element secured to said latter flanged portion and intermediate portion between said flanges.

MARY C. HOLTER.
